SILENCING MEANS FOR VALVE
STRUCTURES

Joseph Alcorn, Seminole, Okla.

Application July 14, 1943, Serial No. 494,656

2 Claims.

(Cl. 123—90)

This invention relates generally to improvements in valve structures for internal combustion engines, and more specifically to means for silencing the operation of the overhead valves used in valve-in-head engines.

The primary object of the invention is to provide simple, inexpensive and practical means for taking up the lost motion and clearance present between the valve rockers and other parts of such valve structures and holding the rockers in firm contact with the tappets or pushrods, all to the end of reducing, or eliminating the tapping noises usually attending the operation of the valves.

Another object is to provide means of this nature which is readily applicable to existing valve rocker mechanisms without any structural alteration thereof and requiring only slight changes in the means usually provided for clearance adjustment to compensate for the addition of my silencing means.

With these and other objects in view, the invention resides in the novel construction and arrangement of parts as hereinafter fully set forth and claimed, reference being had to the accompanying drawing wherein

Figure 1 is a side view of a valve rocker mechanism of conventional form, equipped with the silencing means of my invention;

Figure 2 is a top plan view thereof;

Figure 3 is a side, or edge view of the silencing means alone, this view showing only the spring device forming the major part of such means;

Figure 4 is a top plan view of the device of Figure 3;

Figure 5 is a vertical cross sectional view along the line 5—5 in Figure 1;

Figure 6 is an inverted plan view of the clamp for mounting the spring device of Figure 3 upon the valve rocker.

Referring now more particularly and by reference characters to the drawing, I have shown my invention as applied to a conventional valve rocker mechanism including a rocker 10 oscillatably mounted on a rocker shaft 11 and having a valve actuating arm 12 at one end arranged over the end of a valve stem 13. At its other end 14, the rocker 10 has a tapped opening 15 in which the usual tappet engaging screw 16 is adjustably mounted. This screw at its lower end engages the tappet or push rod 17 so that the upward movement thereof will oscillate the rocker causing the arm 12 to downwardly engage and dis-

place the valve stem 13 to open the valve (not shown) in usual manner.

To compensate for the expansion of the metal in the valve and stem, a clearance must be provided between the rocker arm and valve stem so that, as the engine heats, the valve will not be held open. The amount of such clearance is adjusted in usual manner by the screw 16 and is locked by the set nut 18 thereon. Such clearance, however, results in lost motion and a tapping noise during the operation of the valve mechanism as is well known, and my invention aims to largely overcome or silence such noises.

My invention accordingly comprises a spring device, designated generally at 19, including a main spring member 20 and a secondary spring member 21, both of which are formed from initially flat, leaf spring material. The member 20 has a flat operating end 22 and a longitudinally extending slot 23 which opens through its other, or mounting, end 24. The slot 23 permits the legs or arms 25, which it forms, of the main spring member to curve upwardly alongside the rocker arm 12, over the hub 26 of the rocker, and to pass alongside the tappet screw 16 beneath the nut 18 thereon, while the operating end 22 of the member is disposed between the end of the rocker arm and the upper end of the valve stem 13, as clearly shown in Figure 1. The arm portion 12 of the rocker is ordinarily narrow (horizontally or parallel with the shaft 11) while the opposite end 14 of the rocker, due to its being provided with the opening 15, is wider and accordingly provides a seat or bearing for the ends of the legs 25 at each side of the screw 16.

The secondary spring member 21 is shorter as herein shown and has an operating end 27 similar to that of the main spring, this secondary spring also having a slot 28 which forms short legs 29 which are riveted or otherwise suitably secured at 30 to the legs 25 intermediate their ends. This operating end 27 of the secondary spring member is disposed over the corresponding end of the main spring and the respective legs 25 and 29 are tensioned so that the ends normally diverge. The ends being properly disposed as herein shown, they will bias the rocker to urge the arm 12 and valve stem 13 apart.

The secondary spring member 21 is herein shown as arranged uppermost to engage the end of the rocker arm 12 and the end portion of the spring has lateral, upturned lugs 31 (Figure 5) which are clamped over the beads or projections 32 usually found on the lower sides of the arm,

to thereby hold both spring members against sidewise displacement relative to the rocker.

The respective operating ends 22 and 27 of the spring members have contact bosses or points 33 and 34 pressed from their adjacent surfaces and toward each other, the contacting faces of these bosses being centrally concaved as shown at 35 to reduce the effective contacting areas to the narrow annular surfaces 36.

The mounting end 24 of the main spring member 20 is engaged by a rectangular clamp or clamp member 37 which has an opening 38 to pass the screw 16 when the clamp is placed over this end of the spring. The clamp further has depending lateral flanges 39 which overhang the sides of the spring and said flanges have inwardly projecting teeth 40 which interlock with any opposed pair of a series of notches formed by teeth 41 along both sides of the spring. Thus the entire spring device may be adjusted lengthwise with respect to the rocker, to bring the contact bosses 33 and 34 properly into alignment with the axis of the valve stem 13, and with the teeth 40 and 41 properly interlocked and the nut 18 turned down, such adjustment will be positively maintained.

It will be apparent that the normally divergent operating ends 22 and 27 of the spring device will yieldably urge or bias the rocker arm 12 and valve stem 13 apart so that all lost motion will be eliminated and tapping noises which would arise from such lost motion will be silenced. The concaved surfaces of the contact bosses 33 and 34 aid in such function by reducing the contact areas involved and by a sort of cushioning effect between the contacts due to the pocketing of air in such concavities as the contacts close.

The device as herein disclosed may obviously be applied to the valve without any structural alteration thereof and only the screw 16 need be adjusted to compensate for the added clearance required between the rocker arm and valve stem

by the positioning of the operating ends of the springs therebetween. This screw 16 will, of course, be adjusted to provide the usual slight clearance between the contact bosses 33 and 34 to permit the expansion of the parts due to heat of the engine.

Having now fully disclosed my invention, what I claim as new and desire to secure by Letters Patent is:

- 10 1. In a device of the kind described for mounting upon a conventional medially pivoted rocker arm of an internal combustion engine, for silencing the operation of a valve thereof, the said rocker arm being adapted at one end for operating the valve stem of the valve and at the opposite end for engaging the conventional tappet by means of an adjustment screw threadedly passed through that end of the rocker arm, and the said adjustment screw carrying a set nut, an elongated flat spring provided with divergent branches at 20 one end for positioning between the valve stem and adjacent end of the rocker arm for biasing these elements oppositely, the opposite end of said spring including a flat and longitudinally slotted mounting portion adapted to engage the said adjustment screw beneath the set nut thereof, and means for adjustably securing this end of the spring in place against longitudinal slippage.
- 15 2. In a device according to claim 1, the said means for securing the spring against longitudinal slippage comprising a flat clamping member centrally apertured for seating over the adjustment screw beneath the set nut and against the slotted flat portion of the spring at that end, the 25 said clamping member having lateral pendant flanges overlapping the margins of the said slotted flat portion of the spring and there being complementary interlocking means on the flanges of the clamping member and contiguous margins 30 of the slotted flat portion of the spring for locking the elements in any set position.
- 35 30
